JAY J. JAKOWSKY, OF WILKINSBURG, PENNSYLVANIA, ASSIGNOR TO C & C DEVELOPING COMPANY, OF KANSAS CITY, MISSOURI, A CORPORATION OF ARIZONA

PROCESS FOR CONVERTING HYDROCARBONS

Application filed July 22, 1934. Serial No. 727,536.

This invention relates to processes for converting hydrocarbons; and it relates more particularly to the conversion or transformation of relatively heavy hydrocarbons, particularly mineral oils, into more useful products of lower boiling point by thermal decomposition or cracking, the operation being aided and supplemented by suitable application of a high tension electrical discharge of 5 the corona type to the hydrocarbons undergoing treatment in the cracking or converting zone.

It has been proposed heretofore to subject relatively heavy mineral oil vapors to the 15 action of a high tension silent or corona discharge for the purpose of decomposing the mineral oil into lower boiling products such as gasoline or other forms of motor fuel. It has been supposed by some that the action of 20 the high tension electrical discharge, when sufficiently high frequencies are employed, would set up molecular vibration of such rapidity and intensity as to bring about the desired breaking down of the larger molecules with resultant production of smaller 25 molecules characterizing lower boiling mineral oil products of the gasoline type. Others have believed that high tension discharge resulting from the use of a current that is 30 chiefly unidirectional would bring about something analogous to electrolytic decomposition of the heavy hydrocarbon compounds, with resultant production of lower boiling substances.

35 The present invention is based upon the discovery that when mineral oil vapors are passed through a suitable decomposing chamber heated to proper cracking temperatures, the efficiency of the thermal decomposition or cracking of the mineral oil vapors can be notably increased by applying to the 40 vapors passing through the converting or cracking zone a high tension electrical discharge of the corona type in such manner as to cause precipitation of the thru-going heavy oil particles or the creation of an "electrical wind", particularly if this be done in such a way as to direct the heavy oil vapor 45 particles toward the hot walls of the cracking

zone so that they come into contact with or close proximity thereto.

In the thermal decomposition of mineral oil vapors for production of lower boiling products, the degree of decomposition or 55 cracking attained at any one temperature depends in large measure upon the extent of the heated surfaces to which the vapors are exposed or with which they are brought into contact during their passage through the 60 converting zone which is usually in the form of a tube. Attempts have been made to increase the area of such hot contact surfaces by employing filling material of various 65 kinds in the cracking tube, but this method has generally failed because of stoppage of the tube by heavy carbon and coky deposits on the filling material. On the other hand, in passing through a cracking tube not containing filling material of some kind, the gases 70 and vapors have a tendency to channel, and since the interior of the vapor space is at a temperature lower than the heated walls of the cracking tube under the conditions assumed, much less cracking takes place in the 75 main body of the vapors than occurs in close proximity to the hot tube walls where the vapors are practically in physical contact with said walls.

It has now been found that if the physical 80 condition of the vapors passing through an unfilled or unobstructed cracking tube be properly controlled, this channeling or 85 stratification of vapors within the tube can be done away with, and other useful and important effects attained, by application of a suitable high tension electrical discharge of 90 the corona type. As applied in the practice of the present invention, this high tension discharge is believed to act mainly in much the same way that it is generally understood 95 to act in precipitating processes and apparatus of the well known Cottrell type. That is to say, just as the particles of dust or liquid are driven from the central fine-wire discharge electrode of the Cottrell precipitating apparatus toward the collecting plate, so in an analogous manner may particles of mineral oil in a sufficiently saturated vapor of such oil be driven toward the heated walls of 100

a cracking chamber, such as a tube, thereby breaking up the before-mentioned channeling of the vapors and not only ensuring efficient contact of the heavy hydrocarbons with 5 said heated walls but also rendering the temperature throughout the cross-section of the tube more nearly uniform than would otherwise be possible. As a result, it becomes unnecessary to overheat the cracking tube in 10 order to attain suitable cracking temperatures near the axis of the tube. However, in order to attain results of practical importance by this method, it is essential to so control the operating conditions that the heavy 15 hydrocarbon compounds which it is desired to decompose or crack may be in such physical condition or state that they may be efficiently susceptible to the precipitating or directing action of the high tension electrical 20 discharge in question. It has been found that upon substances existing in true gaseous condition, as distinguished from the condition of a mist or fog or analogous vapor form, a high tension electrical discharge has 25 little or no precipitating or directing effect, and that accordingly no effective precipitation results from the application of said discharge to substances in true gaseous condition. It seems to be essential that in order 30 for such precipitating or directing action to occur, the substance subjected to the electrical discharge must exist in the form of molecular aggregates, such as particles or droplets of appreciable size like those characterizing for 35 example, a visible mist or fog. This means, in treating a mineral oil, for example, that under given conditions the temperature must not exceed a certain critical point at which the most volatile of those heavy hydrocarbon 40 constituents which it is desired to convert change from molecular aggregates, tangible particles or droplets into true gaseous condition. For the purposes of this invention, therefore, the optimum condition is where 45 the vaporized mineral oil passing through the cracking or converting zone contains a maximum proportion of such aggregates, particles or droplets in the form of mist or fog. In this condition the vaporized mineral 50 oil may be compared to steam in the condition of saturation or wetness, superheating of the vaporized mineral oil being absent or minimized.

Since the high tension electrical discharge 55 has little or no precipitating effect upon true gases, the progress of gasoline or similar low boiling products through the cracking tube, which is heated to above their critical points, is unimpeded by the high tension electrical 60 discharge which acts selectively upon the particles of the heavy oil fog or mist and drives them toward the tube walls. As a result, the gasoline and other low-boiling products pass rapidly out of the cracking tube and are not 65 subjected in large measure to the cracking

effect due to delayed passage through the cracking zone or to excessive contact with the hot tube walls, while the high-boiling hydrocarbons are held back by continually being precipitated against hot walls and re-subjected to such cracking conditions. Moreover, such heavy hydrocarbons as may initially escape cracking and would otherwise tend to be carried out of the cracking apparatus under ordinary conditions with the 70 gasoline or other motor fuel product are precipitated and condensed by the action of the electrical discharge and are refluxed to the vaporizer portion of the apparatus. This takes the load off the cooling and condensing 75 system to which the low boiling products pass from the cracking tube and, in effect, increases the capacity of such system. This method of separating and condensing high-boiling constituents of a mixture of vapors 80 and gases by means of a high tension electrical discharge, and then passing the residual gaseous mixture to a cooling system for recovery of a desired condensate, is believed to be broadly new not only in the petroleum 85 art but also in other fields, such as alcohol distillation, where relatively high-boiling constituents of a mixture of distillation vapors and gases are required to be separated 90 from a desired cut or fraction. By "knocking out" such heavier constituents with a high tension discharge before the distillation vapor and gas mixture is passed to the cooling and condensing system, not only is 95 the load on the latter reduced but a sharper 100 separation of heavy products from lighter products is made possible.

In practicing the present invention, the high tension corona or silent discharge may be produced with various types of current, either alternating or direct, and either high or low frequency, the particular type of current employed being ordinarily immaterial. In practice, high tension direct current 105 usually offers advantages. The oil to be converted is vaporized and passed through the cracking tube which is externally heated to a temperature sufficiently high to effect cracking on and closely adjacent the inner walls of the tube, a common range of converting 110 temperatures in vapor phase cracking being from 500° to 700° C. The corona or silent discharge is caused to pass transversely of the path of vapor travel and in effect acts like a trap or filter through which the gasoline and other relatively low boiling products, whose critical points are below the temperature maintained in the cracking zone, pass freely, while the higher boiling products are 115 "knocked out" and driven to or toward the hot walls of the tube and either undergo cracking or are condensed and refluxed to the source of oil vapors. While the employment of pressure on the vapors in the cracking zone 120 is not essential, it is often advantageous for 125 130

certain oils and to recover certain liquid end reaction products, and may amount to 100 pounds per square inch, or more, in a typical instance.

5 It has been found that in operating in accordance with the principles of the invention as herein disclosed, the gasoline or other low-boiling product obtained is substantially lower in unsaturates than is the corresponding 10 product obtained by vapor phase cracking as ordinarily conducted. This is doubtless attributable in part to the fact that the present invention makes it possible to avoid overheating the tube walls and thus effecting unnecessarily drastic cracking in an attempt to obtain 15 large yields of cracked products.

In the most advantageous mode of practicing the invention, it is desirable that the cracking tube contain an appreciable amount 20 of heavy mineral oils in liquid form as well as in the form of vapors, in order that the gas and vapor mixture through which the high tension discharge is passed may be maintained in a condition of maximum saturation 25 or wetness, the desirability of which has already been discussed.

Various forms of apparatus may be employed in carrying out the process of the invention, but in general the employment of a 30 vertical tubular cracking chamber is found to be most satisfactory. One particularly suitable type of apparatus is illustrated more or less diagrammatically in the accompanying drawing which is a central vertical section 35 through a furnace chamber enclosing a plurality of cracking tube units shown in elevation. Referring to the drawing, 10 represents generally a vertical cracking tube unit, of which any suitable number may be housed within a circular shaft furnace whose 40 walls of firebrick or the like are indicated at 11. The cracking tubes, which may be of iron, steel, or other suitable metal, are suspended from near their upper ends by means 45 of supporting collars 12 which rest upon a plate 13 covering the top of the furnace, said plate being in turn-carried upon a steel supporting frame 14 which stands on a suitable foundation, not shown. The construction is 50 such that the entire weight of the cracking tubes is carried by the framework 14 which is outside the furnace and is therefore not subjected to the effects of high heating. An expansion joint 55 provides for slight relative movement between the supporting plate 12 and the furnace walls. Each cracking tube unit has an enlarged lower part 16 adapted to contain a substantial body of liquid and to function as a vaporizer. Adjacent this enlarged lower portion of the cracking tubes 60 is provided suitable firing means such as ring burners 17 for gas or the like, one of which may be provided for each tube. Substantially in the vertical axis of each cracking 65 tube is a fine wire discharge electrode 18, sup-

ported at its upper and lower ends, respectively, by high tension insulators 19 and 20, provision being made at 21 at the upper end of said discharge electrode to connect the same to a high voltage supply of suitable 70 character. The cracking tube may be grounded and constitutes the other electrode, in this instance the collecting electrode. The tube forms at its lower end a settling chamber and is provided with a clean-out and blow-off pipe connection 22—23, the pipe 23 being provided with check valve 24 and shut-off valve 25. Oil may be introduced into the converting tubes either at the top or bottom, but in the installation here illustrated, each 75 tube is supplied with oil through supply pipe 26 having a shut-off valve 26^a, said pipe 26 entering pipe 23 between the tube and valve 25. Valve 25 is of course closed except when the tube is being cleaned out, in which case 80 valve 26^a is closed.

In employing the described apparatus for carrying out the process of the invention, gas oil or the like, most desirably preheated in a preheater (not shown), is fed into each tube 90 unit through pipe 26 until it stands substantially at the lever indicated at 27 in the drawing, or about half fills the lower enlarged portion 16 of each cracking tube. The upper half of this enlarged portion, which may in fact 95 be considered the main cracking and reaction chamber, thus provides a vapor space of substantial volume. The furnace being fired to the proper cracking temperature by means of the ring burners 17, the oil is vaporized in 100 the lower part 16 and passes upwardly through each cracking tube, being subjected meanwhile to the action of the corona discharge maintained between the discharge electrode 18 and the cracking tube walls. The 105 more volatile products leave the cracking tube through outlet pipe 28, which is provided with an adjustably weighted pressure-controlling valve 29 and a check valve 30. The vapors are led by pipe 28 to a cooling 110 system (not shown) which may comprise a dephlegmator (optionally functioning as a preheater for oil fed to the tube) and one or more condensers of any usual or suitable type. The furnace chamber is of course provided 115 with a suitable stack or chimney 31 for waste fire gases.

The proper temperature to be maintained in the cracking tubes depends upon various factors including the particular character of 120 oil being treated, the rate of feed, operating pressure on the vapors, etc.; but in any case, as before stated, the temperature should be somewhat below the critical point at which there ceases to be a distinctly perceptible mist or fog in the lower part of the cracking tube. To enable conditions inside the cracking tube to be observed, peep-holes, properly alined in opposite sides of the tube and protected by 125 suitable heat-resistant glass may be provided, 130

together with a protected opening in the furnace wall through which a strong beam of light produced by a suitable arrangement of electric arc and condensing lens may be projected through the space within the cracking tube. In the arrangement here shown, a housing 32, centrally located within the furnace and suitably protected from the heat, contains a high power source of light; and 5 observation tubes 33, each alined with peep-holes in the corresponding cracking tube and closed at 34 and 35 by suitable glass windows, are directed toward said source of light. By directing the line of sight somewhat to one 10 side of the light beam passing through each observation tube, an observer may readily detect the presence of an oil fog or mist within the cracking chamber if the operating conditions are as contemplated by the present invention. When the converting tubes are being operated to best advantage, the mist or fog is clearly discernible through observation tubes 33. In the upper part of the converter tubes 18, this mist or fog is found to have 15 nearly or quite disappeared owing to the precipitating or filtering action of the high tension discharge.

What is claimed is:

1. The process of converting relatively 30 heavy oils into lower boiling products which comprises vaporizing a relatively heavy oil under conditions such that a substantial part of the resultant vapors is in non-gaseous and substantially saturated condition, and subjecting 35 said vapors, while in operative proximity to a surface heated to a converting temperature substantially above that of vaporization to the precipitating action of a high-tension silent electrical discharge tending to 40 drive such non-gaseous part of said vapors toward said heated surface, and conducting the uncondensed products away for recovery of a desired lower boiling product therefrom.

2. The process of converting oil which 45 comprises passing vaporized oil through a converting zone having walls heated to a converting temperature substantially above that of vaporization and subjecting such vaporized oil, as it passes through said zone to a 50 high tension electrical discharge of the corona type, a substantial part of said vaporized oil existing in the form of visible fog or mist in the converting zone under the conditions of operation, and obtaining a useful fuel condensate from the volatile products leaving 55 said converting zone.

3. The process of converting oil for production of a relatively volatile liquid motor fuel which comprises passing a substantially 60 saturated vaporous mixture of mineral oil hydrocarbons through a walled zone maintained at a converting temperature which is above the critical gasifying point of the motor fuel to be produced but below the critical gasifying points of materially higher-boiling

products, subjecting said vaporous mixture as it passes through said zone to the precipitating action of a high tension silent electrical discharge, whereby ungasified hydrocarbon aggregates are driven toward the walls of 70 said zone said walls being maintained at a converting temperature substantially above that at which said vaporous mixture was evolved, and condensing a motor fuel from the volatile mixture leaving said zone. 75

4. The process of converting oil into lower boiling products, which comprises heating a liquid body of mineral oil to produce vapors therefrom comprising both gaseous and non-gaseous constituents said non-gaseous constituents being in substantially saturated vaporous condition, passing the resultant vapors, while still substantially in the presence of said liquid body of oil, through a zone having walls maintained at a converting temperature substantially above that at which said vapors were evolved, and simultaneously passing a high tension silent electrical discharge through said vapors and thereby driving non-gaseous constituents thereof into effective proximity with said walls to effect conversion of said constituents, while permitting gaseous constituents to pass through said zone substantially without interruption, and recovering a relatively low boiling condensate from the volatile products leaving the converting zone. 85

In testimony whereof I hereunto affix my signature.
